UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,076,878.

Specification of Letters Patent. Patented Oct. 28, 1913.

Application filed July 27, 1911. Serial No. 640,836.

To all whom it may concern:

Be it known that I, ANDREW EPPLER, a citizen of the United States, residing at Lynn, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The invention relates to welt sewing machines such as are used in the manufacture of boots and shoes, and more particularly to devices for severing the welt at the completion of the sewing operation, and holding the severed end in proper position for attachment to a shoe at the beginning of the next sewing operation, and to devices co-operating therewith.

Welt severing and holding devices as heretofore constructed have been arranged to sever the welt at a predetermined point beyond the welt guide, and have been operated to release the severed end of the welt after the needle has drawn the first loop of thread through the work, and before the initial feed of the work takes place. With this construction and mode of operation the welt is liable to be drawn away from the shoe when the welt guide is withdrawn preparatory to the feed of the shoe, and especially in machines like the Goodyear turn and welt machine, in which the welt guide is withdrawn after the needle has been retracted and is held in its rearward position during the feed.

It is accordingly one object of the invention to provide welt severing and holding devices having a novel and improved construction and mode of operation whereby the proper attachment of the end of the welt to the shoe is insured.

To this end one feature of the invention contemplates the provision in a welt sewing machine of welt severing and holding devices which continue to hold the end of the welt during at least one cycle of operations of the machine so that the welt is held against displacement in a uniformly reliable manner until its end has been secured to the shoe. In this construction the welt holding devices remain in engagement with the welt during at least the initial feed of the shoe, and they are so mounted that they move with the shoe during its feeding movement and

maintain the welt in proper position with relation to the shoe, and insure the proper drawing of the welt through the welt guide when the guide is retracted and during the feed of the shoe.

Further features of the invention relate to the construction and mode of operation of the devices which determine the extent to which the welt may be drawn forward in removing the shoe preparatory to severing and holding the welt, and to the construction of the devices for severing and holding the thread.

The various features of the invention will be understood from an inspection of the accompanying drawings and the following detailed description of the mechanism illustrated therein.

In the drawings Figure 1 is a left-hand side elevation of a welt and turn sewing machine embodying the various features of the invention in their preferred forms; Fig. 2 is a front elevation of the machine; Fig. 3 is a detail sectional elevation showing a part of the welt severing and holding devices; Fig. 4 is a plan view showing the welt severing and holding devices, parts of the machine being broken away or omitted for the sake of clearness; Fig. 5 is a detail plan view showing the mechanism for rendering active the devices for determining the extent to which the welt is withdrawn in removing the shoe; Fig. 6 is a plan view partly in section showing the welt holding and severing devices in advanced position; Fig. 7 is a sectional elevation on line 7—7, Fig. 6; Fig. 8 is a vertical sectional view on line 8—8, Fig. 6; Fig. 9 is a vertical sectional view through the devices for determining the forward movement of the welt; Fig. 9^a is a detail sectional view on line 9^a—9^a, Fig. 7; Fig. 10 is a sectional view on line 10—10, Fig. 9; Fig. 11 is a detail front view of the devices for severing and holding the thread; and Fig. 12 is a sectional elevation on line 12—12, Fig. 11, looking in the direction of the arrow.

In the drawings the invention is shown embodied in the welt and turn sewing machine shown and described in my prior application Serial No. 447,542, filed August 8, 1908. This machine is provided with the curved hook needle 1, the looper 2, the thread finger 3, the feed point 4, the channel guide 5, the welt guide 6, and the back gage 7, which are operated in the well known

manner to unite the insole, upper and welt by a chain stitch seam.

The devices for severing and holding the welt comprise the welt gripping jaws 8 and 9 and the welt severing knife 10 which are held in retracted position during the sewing of the shoe, and are advanced to sever and hold the welt after the sewing operation has been completed and the machine has been brought to rest with the stitch forming devices in position for the removal of the shoe. The welt holding jaws are carried upon the front end of a bar 11 mounted to slide in a carrier arm 12 which is mounted to swing about a vertical shaft 13. The shaft 13 is mounted in a bearing in a fixed bracket 14, and the carrier arm 12 is held in normal position against a stop 15 by a spring 16. The upper jaw 8 of the welt holder is formed by the projecting front end of the bar 11, and the lower jaw 9 is formed on the front end of a lever 17 pivoted to the bar by means of an eccentric pivot 18 which may be turned to adjust the jaw 9 with relation to the jaw 8. The bar 11 is recessed to form a guide for the knife carrying bar 19, to the forward end of which the knife 10 is secured. The knife carrying bar is provided at its forward end with a cam surface 20 arranged to engage the rear end of the lever 12 and actuate the lever to close the welt holding jaws. The rear end of the lever 17 is slotted at 21 to form a spring arm 22 so that the jaw 9 is yieldingly forced against the welt.

The gripper carrying bar 11 is advanced and retracted through a gear segment 23 secured to the shaft 13 and engaging a rack 24 formed on the bar. The cutter carrying bar 19 is independently reciprocated by a pinion 25 secured to the shaft 13 and engaging a rack 26 formed on the bar. The shaft 13 is rocked to advance and retract the welt holding jaws and cutter through a reciprocating rack bar 27 arranged to engage a pinion 28 secured to the upper end of the shaft 13. The rack bar is actuated through a bell crank lever 29, one arm of which is connected through a rod 30 with a treadle (not shown), and the other arm of which is connected with the bar 27 by means of a pin 31 engaging a slot 32 in the arm. The gripper and cutter carrying bars are held in retracted position by a spring 33 connected with the bell crank lever 29. When the bars are in this position the lower jaw of the welt gripper is held in open position by the engagement of the rear end of the lever 17 with a fixed cam lug 34.

When the welt is to be severed and held, the operator depresses the treadle connected with the rod 30, thereby raising the rod and rocking the shaft 13 in a direction to advance the gripper and cutter bars. The bars move forward in unison until the jaws of the welt holder have passed on opposite sides

of the welt, and the guard 35 on the lower jaw has engaged the inner edge of the welt. When the gripper bar reaches this position the teeth of the gear segment 23 pass from engagement with the teeth of the rack 24, and the bar is held locked in position by the engagement of a locking segment 36 formed on the gear with a locking segment 37 formed on the bar. During the continued movement of the shaft 13 the gear 25 continues to advance the cutter bar 19. During the first part of the advance movement of the cutter bar with relation to the gripper bar, the cam 20 on the front end of the cutter bar actuates the gripper lever 17 to close the jaws of the gripper, and then during the continued forward movement of the cutter bar the knife 10 acts to sever the welt. The parts are now in the position indicated in Fig. 6 and in dotted lines in Fig. 4, with the welt holding jaws firmly gripping the severed end of the welt supply beyond the welt guide and holding it in proper position for attachment to a shoe at the beginning of the next sewing operation. The parts are held in this position by a latch 38 pivoted to the bracket 14 and arranged to engage the front end of the actuating rack bar 27 when this bar is in its retracted position. The latch 38 is drawn yieldingly forward into position to engage and hold the rack bar 27 by a spring 39. At the beginning of the sewing operation upon the next shoe, the welt holding jaws continue to hold the end of the welt until after the welt guide has been withdrawn from the shoe and until the initial feed of the shoe has been completed, and during the feed of the shoe the arm carrying the cutter and gripper bars is swung about the shaft 13, so that the welt holding jaws move forward with the shoe and hold the end of the welt in proper relation to the shoe, and also draw the welt through the welt guide so that all danger of displacing the welt is avoided. In the construction shown, the carrier for the welt holding gripper is actuated to move the gripper with the shoe during the initial feed through connection with the feed slide 40 which carries the awl and channel guide. As shown, this connection comprises a bar 41, one end of which is adjustably secured to the feed slide through a split bearing and clamping bolt 42 (Fig. 1), and the other end of which is provided with a depending finger 43 arranged to coöperate with a yielding dog 44 carried by the gripper bar. The dog 44 is pivoted on the gripper bar and is held in normal position by a spring 45. This yielding dog is provided in order that the welt holding gripper may not be moved laterally by the slight forward movement of the feed slide which occurs upon starting the machine prior to the initial advance movement of the needle.

When the machine is brought to rest at the completion of the sewing operation with the parts in position for the removal of the shoe, the feed slide is usually in such position that it will move forward slightly when the machine is started. With the feed slide in this position, the finger 43 is in the path of the dog 44 when the gripper carrying bar is advanced to bring the jaws of the welt holder into position to grip the welt, and the dog 44 yields and rides under the end of the finger. When the machine is started the finger still rides on the top of the dog 44 when the feed slide is given its slight forward movement, but on the return movement of the feed slide, preparatory to the initial feed of the shoe, the finger 43 passes to the right of the dog 44 so that the dog snaps up into position in front of the finger. Now during the advance movement of the feed slide in giving the initial feed to the shoe, the finger 43 bears against the side of the dog 44 and swings the arm 12 about the shaft 13, thus moving the welt holding jaws with the shoe during its initial feed. During this movement of the carrier arm 12 the lug 46 on the side of the arm engages an adjusting screw 47 carried by the latch lever 38, and swings the latch 38 in a direction to release the actuating rack bar 27. The parts are so adjusted that the release of the rack bar takes place as the feed of the shoe is completed, and the spring 33 acts to rock the shaft 13 and retract the gripper and cutter bars. During this movement of the rock shaft 13 the gear 25 first retracts the cutter independently of the gripper bar, and then the cutter and gripper bars are moved in unison to their rearward position. The movement of the cutter bar with relation to the gripper bar causes the cam 20 to release the jaw 9 of the gripper so that the gripper may swing away from the welt, and during the return movement of the gripper bar the end of the gripper lever 17 rides up the cam lug 34 so that the jaw 9 is positively opened. The return movement of the gripper bar also withdraws the dog 44 from engagement with the finger 43, so that the carrier arm 24 is free to be returned to normal position against the stop 15 by the spring 16. This brings the parts into their normal position where they remain during the completion of the sewing operation, and until the gripper and cutter bars are again advanced to sever and hold the welt.

In order that the welt may be severed at a suitable distance from the end of the completed seam without waste of welting, devices are provided for determining the extent to which the welt may be advanced or pulled through the welt guide in withdrawing the shoe preparatory to the operation of the welt severing and holding devices. In the construction shown, the de-

vices for determining or limiting the forward movement of the welt are rendered active or thrown into operation by the reverse movement imparted to the cam shaft of the machine in freeing the needle from the loop and bringing the parts into position for the removal of the shoe, and are rendered active by the forward movement of the cam shaft at the beginning of the next sewing operation. The devices are thus rendered active at the proper time without any attention or care on the part of the operator, and are inactive during the normal operation of the machine.

As shown, the welt W is led to the welt guide over a guide pulley 48 which is mounted to turn freely on a controlling or measuring sleeve 49. The sleeve 49 is mounted upon a fixed stud 50 and carries a clamping jaw 51 adapted to engage and clamp the welt against the pulley 48. The clamping jaw 51 is carried on one arm of a bell crank lever 52, the other arm of which is arranged to be engaged by the end of a plunger 53 mounted within the stud 50. The clamp is held normally out of engagement with the welt by a spring 54. The movement of the measuring sleeve 49 on the stud 50 is limited by a stop pin 55 secured to the sleeve and arranged to play within a slot 56 formed in a stationary disk 57. The disk is held in fixed position between a shoulder on the stud 50 and the surface of the bracket 58 in which the stud is mounted. The stop pin is held normally in engagement with one end of the slot 56 by a torsional spring 59, one end of which is connected to a flange on the end of the stud, and the other end of which is connected with the measuring sleeve. The clamp actuating plunger 53 is formed in two sections separated by a spring 60 which may yield as the plunger is advanced in forcing the clamp against the welt. The rear end of the plunger is engaged by a cam shoe 61 adjustably secured to the rear end of an arm 62 by a set screw 63. The arm 62 is carried by a rock shaft 64 which also carries an arm 65 arranged to be engaged and operated by the lever 66 through which the tension is thrown off when the machine is reversed at the end of the sewing operation. The lever 66 carries an arm 67 provided with bearing surfaces 68 and 69 which are adapted to bear against a disk on the cam shaft 70 of the machine. The disk is provided with an actuating notch 71 which engages the shoulder between the bearing surfaces 68 and 69 when the machine is reversed, and forces the arm 67 back, thus rocking the bell crank lever 66 to throw off the tension in the usual manner. When the lever 66 is thus rocked it acts upon the arm 65 and rocks the shaft 64 in a direction to force the cam 61 against the end of the plunger 53 and force the plunger forward.

This movement of the plunger rocks the bell crank lever 52 and forces the clamp 51 against the welt, and thus connects the welt and pulley 48 with the measuring disk 49, so that these parts are held against relative movement. Now when the shoe is drawn forward to draw the welt through the welt guide, the measuring sleeve 49 is rotated against the tension of the spring 59 until the pin 55 engages the end of the slot 56, when further advance movement of the welt is prevented. The length of the slot 56 therefore determines the extent to which the welt may be drawn forward in removing the shoe and bringing the welt into proper position for the operation of the welt severing and holding devices. When the machine is started, the arm 67 is swung into normal position as indicated in Fig. 1, and the lever 61 is swung away from the end of the plunger 53 so that the welt clamp is released and is disengaged from the welt by the spring 54. The measuring sleeve 49 immediately returns to normal position under the influence of the spring 59, and the welt is free to pass over the pulley 48 and the pulley is free to rotate about the measuring sleeve during the sewing operation.

The devices for severing and holding the thread after the welt has been severed consist of a spring clamping plate 72 and a knife 73 projecting from the plate. The clamping plate is secured to the looper 2 and co-operates with the surface of the looper in clamping the thread, as indicated in Figs. 11 and 12. After the welt has been severed, the shoe is manipulated by the operator to carry the thread between the plate 72 and the surface of the looper, and then by a downward movement of the shoe the thread is carried across the edge of the knife 72 and severed. The knife 72 is so arranged that a short length of free thread is provided beyond the clamping plate. During the initial loop drawing stroke a part of this free thread will be drawn through the holding device, and the free end of the thread will therefore be held under tension during the drawing of the loop, and thus a tight initial stitch will be formed.

When the parts are in the proper position for the removal of the shoe, the thread finger is in substantially the position indicated in Figs. 11 and 12, and the thread is liable to pass up the shank of the thread finger when it is carried up into the thread holding device. If this should occur the thread finger would not operate properly upon the thread in forming the first stitch. In order to insure the proper engagement of the thread finger with the thread, the finger is provided with a spur or projection 74 under which the thread passes, and which operates to retain the thread in proper position with relation to the thread finger, and insures the

proper action of the thread handling devices when the machine is started.

While it is preferred to employ the specific construction and arrangement of the parts shown and described, it will be understood that this construction and arrangement is not essential, and may be varied or modified without departing from the broader features of the invention.

Having explained the nature and object of the invention, and specifically described one form of machine in which it may be embodied, what I claim is:—

1. A sewing machine, having, in combination, stitch forming mechanism, devices for severing and holding the welt at the completion of the sewing, and means for maintaining the holding devices in engagement with the welt during at least one cycle of operations of the machine at the beginning of the sewing operation, substantially as described. 80

2. A sewing machine, having, in combination, stitch forming mechanism, welt severing and holding devices, mechanism for actuating the devices to sever and hold the welt at the completion of the sewing operation and to hold the end of the welt during at least the initial feed of the work at the beginning of the succeeding sewing operation, substantially as described. 90

3. A sewing machine, having, in combination, stitch forming mechanism, welt severing means, welt holding devices for holding the end of the welt, mechanism for operating said means and devices to sever and hold the welt at the completion of the sewing, and means for moving the holding devices with the shoe during the initial feed of the shoe and for disengaging the holding devices from the welt after the end of the welt has been secured to the shoe, substantially as described. 95 100

4. A sewing machine, having, in combination, stitch forming mechanism, welt severing and holding devices mounted for movement with the shoe, and means for operating the devices to sever and hold the welt at the completion of the sewing operation, substantially as described. 110

5. A sewing machine, having, in combination, stitch forming mechanism, welt severing and holding devices mounted for movement with the shoe, means for advancing and actuating the devices to sever and hold the welt at the completion of the sewing operation, and mechanism for automatically disengaging and retracting the devices after the end of the welt has been attached to the shoe, substantially as described. 115 120

6. A sewing machine, having, in combination, stitch forming mechanism, welt severing and holding devices mounted for movement with the shoe, means for advancing and actuating the devices to sever and hold the welt at the completion of the sewing 125 130

- operation, and mechanism for disengaging and retracting the devices and returning them to initial position after the initial feed of the shoe, substantially as described.
- 5 7. A sewing machine, having, in combination, stitch forming mechanism, a welt severing device, welt holding devices, mechanism for advancing and actuating the devices to sever and hold the welt, mechanism for moving the welt holding devices in the direction of the feed of the shoe, and mechanism for retracting the cutting and holding devices and returning them to initial position, substantially as described.
- 10 8. A sewing machine, having, in combination, stitch forming mechanism, welt holding jaws, mechanism for advancing and retracting the jaws, a welt severing knife, and means operated by the advance of the knife to close the jaws on the welt, substantially as described.
- 15 9. A sewing machine, having, in combination, stitch forming mechanism, a carrier mounted to move in the direction of the feed of the shoe, a reciprocating welt gripper mounted in the carrier, a reciprocating cutter also mounted in the carrier, mechanism for reciprocating the grippers and cutter, and mechanism for actuating the carrier, substantially as described.
- 20 10. A sewing machine, having, in combination, stitch forming mechanism, a reciprocating gripper bar carrying relatively movable welt gripping jaws, and a reciprocating cutter bar provided with means for closing and releasing the jaws, substantially as described.
- 25 11. A sewing machine, having, in combination, stitch forming mechanism, a gripper bar provided with relatively movable welt gripping jaws, a cutter bar provided with means to actuate the gripper jaws, and mechanism for advancing and retracting and relatively reciprocating the bars, substantially as described.
- 30 12. A sewing machine, having, in combination, stitch forming mechanism, a reciprocating gripper bar provided with relatively movable welt gripping jaws, a reciprocating cutter bar provided with a cam for closing the jaws, and a fixed cam for opening the jaws, substantially as described.
- 35 13. A sewing machine, having, in combination, stitch forming mechanism, a reciprocating gripper bar provided with relatively movable welt gripping jaws, a rack and locking segment on the bar, a reciprocating cutter bar, a rack on the bar, and a rock shaft carrying a gear segment and locking
- 40 segment engaging with the rack and segment on the gripper bar and also carrying a gear engaging rack on the cutter bar, substantially as described.
- 45 14. A sewing machine, having, in combination, stitch forming mechanism, a carrier mounted to swing in the direction of the feed of the shoe, a gripper bar mounted in the carrier, a cutter bar also mounted in the carrier, a rock shaft arranged concentric with the pivotal axis of the carrier, pinions carried by the shaft engaging racks formed on the bars, and a locking segment on the shaft engaging a locking segment on the gripper bar, substantially as described.
- 50 15. A sewing machine, having, in combination, stitch forming mechanism, and means for determining the amount of welt drawn forward in the removal of the shoe rendered active by the reversal of the machine, substantially as described.
- 55 16. A sewing machine, having, in combination, stitch forming mechanism, means for limiting the withdrawal of the welt upon the removal of the work, and means operated by the reversal of the machine for rendering said limiting means active and operated by the forward movement of the machine for rendering said means inactive, substantially as described.
- 60 17. A sewing machine, having, in combination, stitch forming mechanism, a welt measuring device mounted for limited movement with the welt, means for connecting the device with the welt at the completion of the sewing and for disconnecting the device from the welt and returning it to initial position at the beginning of the sewing operation, substantially as described.
- 65 18. A sewing machine, having, in combination, stitch forming mechanism, a welt engaging device having a limited movement with the welt, means engaging the device with the welt at the completion of the sewing operation, and means for disengaging the device from the welt at the beginning of the sewing operation, substantially as described.
- 70 19. A sewing machine, having, in combination, stitch forming mechanism, a guide roll for the welt, a measuring sleeve having a limited forward movement, and means for connecting the welt, roll and sleeve at the completion of the sewing, substantially as described.
- 75 20. A sewing machine, having, in combination, stitch forming mechanism, a guide roll for the welt, a sleeve on which the roll is mounted, a welt clamp on the sleeve, a stop for limiting the forward rotation of the sleeve, and means for engaging the clamp with the welt at the completion of the sewing, substantially as described.
